Patented Nov. 25, 1975

237,782

DIGITAL CLOCK HOUSING

Gordon T. Guth, Evanston, and Richard K. Thomas, Elk Grove Village, Ill., assignors to Sunbeam Corporation, Chicago, Ill.

Filed Sept. 4, 1973, Ser. No. 394,205

Term of patent 14 years

Int. Cl. D10—01

U.S. Cl. D10—15

Fig. 1.

Fig. 2.

Fig. 3.

Fig. 4.

FIG. 1 is a left front perspective view of a digital clock housing showing our new design;

FIG. 2 is a top plan view thereof;

FIG. 3 is a front elevational view thereof; and

FIG. 4 is a right side elevational view thereof.

The rear side of the digital clock housing is conventional and unornamental.

We claim:

The ornamental design for a digital clock housing, as shown and described.
